UNITED STATES PATENT OFFICE.

HARRIET GODFREY EMERY AND MARGARET CATE FULLER, OF BOSTON,
MASSACHUSETTS.

IMPROVEMENT IN COLLARS.

Specification forming part of Letters Patent No. 105,442, dated July 19, 1870.

To all whom it may concern:

Be it known that we, HARRIET GODFREY EMERY and MARGARET CATE FULLER, of Boston, in the county of Suffolk and State of Massachusetts, have invented a new and useful Improvement in Cloth and Paper Collars; and we do hereby declare that the following is a full and exact description of the same, reference being had to the accompanying drawing, and to the letters of reference marked thereon.

This invention consists of a collar constructed of two parts of similar shape, one of which forms the collar proper, and the other a yoke, which is intended to slip under the outer garment for the purpose of securing the whole in place. The parts being similar in shape, the outer part, used as a collar, when soiled may be placed inside to serve as the yoke, while the other takes its place upon the outside.

In the drawing a perspective view of our improved collar is shown.

To enable others skilled in the art to make and use our invention, we now proceed to describe fully the construction of the same.

d and *e* represent the parts of the collar.

The part *d* is intended to be slipped under the outer garment, for the purpose of securing the whole in place. When the part *e* becomes soiled, the position of the parts may be reversed, and the part *d* serve as a collar, while the part *e* is employed to retain the whole in place. By means of this construction a cheap collar is produced, which is not only capable of double use, but which will also securely and smoothly retain its place though secured by a single button.

We do not claim, broadly, the idea of securing collars in place by means of a strip projecting beneath the outer garment, for this we know to be old; but,

Having thus fully described our invention, what we claim as new, and desire to secure by Letters Patent, is—

The duplex collar *d e*, when constructed as described, for the purpose set forth.

This specification signed and witnessed this 28th day of February, 1870.

H. GODFREY EMERY.

M. C. FULLER.
